UNITED STATES PATENT OFFICE.

CHARLES T. FORD, OF WASHINGTON, DISTRICT OF COLUMBIA.

LIQUID-CONTROL COCK.

Application filed November 19, 1923. Serial No. 675,764.

The present invention relates to cocks for handling fluids, either gaseous or liquid, and, as here shown and described for the purpose of disclosing the invention, is depicted as used in connection with the charging and discharging of containers for lethal or other gases. It will be understood, however, that it may be adapted to uses other than the specific use herein set forth. For example, and as one other use of the invention, it is shown as applied to a main for the transmittal either of gaseous or liquid products.

Furthermore, the structure and design of the cock may be varied from that found in this illustrative embodiment, and still be within the range of my invention.

The object of this invention is to provide a cock of such construction that it may be utilized for charging a container from a suitable supply; which may be used for discharging the gas stored in the container as it may be needed; which will prevent the escape of gas from the container under normal conditions of pressure while the containers are in use, transport, or storage; but which, if abnormal pressures are generated in the container, as, for example, by heat, and danger of explosion is imminent, will automatically release and bleed the gas off.

In the use, storage, and transport of lethal, noxious, or expensive gases, it is essential that the containers be so constructed and so fitted with control cocks, that the gas may be readily charged into the container from a supply; that it may be readily discharged through the same cock; that danger of leakage be eliminated, and that provisions for relief if container pressure runs up to the danger point, be made.

These are standard official requirements, and I. C. C. regulations in connection with the handling of gases of these types.

I accomplish these objects by the cock construction which is illustrated in the drawings herewith, and which will now be described and claimed.

In the drawings:—

Fig. 1 is a plan view of a cock of my invention.

Fig. 2 is a substantially central vertical section of the cock.

Fig. 3 is a view similar to Fig. 2, showing a modified form.

Fig. 4 is a similar sectional view showing a still further modification.

Fig. 5 is a view showing the application of the cock to a main.

Figure 6 is a central vertical section of a modification of the cock.

Referring to the drawings by numbers, like numbers indicating like parts in the several views, 10 indicates a cock-body of such size and dimensions as may be needed. In said body is formed a key seat 11, here shown, and preferably, tapered. From each end of the body 10 project threaded nipples 12 and 13, the threads on these nipples being preferably of different pitches. Projecting from one side of the body 10 is a third threaded nipple 14 for attaching the cock to a container, and the nipple 14 has a passage 15 traversing it and opening into the key seat 11.

Mounted in the key seat 11 is a key 16, here shown as tapered, and this form is preferable, although other forms might be used, for the reason that, when inserted in the seat 11, it fits snugly and gives a close turning engagement of seat and key. The area of contact between key and seat is considerable, in order to give a sufficient length to ensure against creeping and escape of gas past the key. The key 16 is provided with a passage 17 traversing it lengthwise for a portion of its length, and connecting by a radial passage with the passage 15 in the nipple 14 when the key is turned to proper position.

The passage 17 may take various positions and directions. It may be formed centrally of the key 16, as in Figure 2; it may be inclined, as in Figure 3; or it may be off-centered, as in Figure 4. The advantage of the arrangement shown in Figure 4 is that the pressure area subject to gas pressure coming from the container through passage 15 when the cock is open to the atmosphere, and which pressure tends to unseat the key longitudinally, is considerably reduced. The area subject to unseating pressure is the wall of the radial passage leading from the passage 17 to the outer wall of the key. In Fig. 2 its area is substantially the radius of the key. With the off-centered passage of Fig. 4, it is materially less, and the key-opening effect of gas pressure is correspondingly reduced.

While the relatively long key and key seat, fitted snugly, as described, make for efficient sealing against escape of gas, I have guarded still further against the possibility of gas leakage by providing each of the nipples 12 and 13 with sealing caps 18 and 19.

These caps may take various forms, and are here shown as hexagonal for wrench engagement. The cap 18 will, by preference, have an opening 20 through which a suitable 5 tool may be inserted to engage a socket 21 in the key so that said key may be turned to open or closed position. Beneath cap 18 will be placed an annular packing 22 of suitable material which will seal very completely the 10 joint between the key and its seat.

The cap 19 may be a solid cap, such as is shown in Fig. 3, with sealing material 23 beneath it, or it may be of the relief type 24 shown in Figs. 2 and 4. In the last mentioned 15 form, there will be provided an annular packing 25 surrounding the mouth of passage 17 and sealing the key and seat joint, and adjacent said packing will be a frangible disk 26, which, under excessive gas pressure, will 20 puncture or break and relieve the container of bursting pressure. To permit escape of gas in event of fracture of the disk 26, the cap 24 will be provided with a discharge passage 27 leading from the mouth of the key passage 17 25 to atmosphere. Preferably the atmospheric connection will be by way of laterally disposed passages 28 delivering at the edges of the cap. This increases capacity of discharge and diffusion from the relatively large central 30 discharge passage 27, and prevents also, direct jet discharge action through the top of the cap.

The threads on the nipple 13 will be so 35 formed as to provide for coupling a hose to the cock for charging or discharging a container, and may be made of different pitch or lead from those on the nipple 12, so that danger of mixing up and wrongly applying the sealings caps will be eliminated.

While I have shown the discharge passage 40 and the sealing caps as arranged with a view of using the small end of the key as the discharge end, it will be obvious that the discharge passages and sealing caps might be reversed so that the large end of the key would 45 be the discharge end as illustrated in Figure 6.

This arrangement, where a taper key and seat is used, would have the advantage that 50 gas pressure standing against the key would tend always to force the key into its taper seat, instead of tending to unseat it.

In use the cock will be fitted to a container by screwing the attaching nipple 14 into a 55 suitably threaded orifice in the container, care being taken, of course, that a gas tight joint is secured. The cap may then be removed from the nipple 13, and a hose leading from a suitable supply coupled to the nipple 13. The key 16 will then be turned to the position 60 shown in Fig. 2, with the nipple passage 15 and the key passage 17 in register. The supply of gas may then be turned on and pass to the container through the cock until container pressure has been brought to the desired 65 pressure. The key 16 will then be

turned to close the nipple and key passages, and the hose uncoupled.

The nipple 13 may then have applied to it the solid cap 23 (Fig. 3), or the relief caps 24 (Figs. 2 and 4).

The solid cap 23 may be used under some conditions, but in transport or storage, the safety caps 24 are preferable. With safety caps any increase in container pressure beyond a certain point, for example, increase by 70 expansion under heat, will be automatically taken care of, as described, and danger of explosion of the container done away with.

After the cap 24 has been applied, the key 16 may then be turned to open position with 75 pressure standing against the frangible element of the cap 24. In this condition, the container will be ready for transport, storage, or use.

When it is desired to draw off the contents 80 of the container, the key 16 will be thrown to cut-off or closed position; cap 24 removed, and discharge hose attached. The key 16 will then be turned to discharge position and the desired amount of gas drawn off.

In Fig. 5 is illustrated the application of 85 this cock to a main designed for the transmittal of either gaseous or liquid materials. The main, which may be a gas or liquid transmitting main, must be frequently, in fact generally, tapped, and the cock inserted 90 while the main is full and under pressure. It is customary to attach the well known corporation cock under such conditions by means of appropriate tapping machinery. In order to adapt my cock to the tapping of mains, the body of cock may be provided with a projection 29 at its top which may be threaded internally or externally, as here shown, to receive the cock inserting tool of the tapping 95 machine. This projection 29 will be in line with the nipple 30 by which the cock is attached to the main 28 and threaded reversely from the threads on the nipple 30, so that the insertion and removal of the cock may be 100 readily accomplished.

With the cock in place, as shown in Fig. 5, it will be observed that the delivery end 31 lies 105 relatively close to the main, as distinguished from projecting from the top of the cock, as in ordinary constructions, and from this closely adjacent delivery end the lead off or service pipe 32 will extend, a suitable coupling 110 being provided for attaching the pipe to the delivery end of the cock. The advantage 115 of bringing the delivery end of the cock and the lead off pipe close to the main is, that these mains are laid in trenches with lateral 120 trenches for the lead off or service pipes, which are connected with the cock, and by arranging for attachment of the service pipe 125 close to the main there is less leverage, and, consequently less danger of breakage, from the weight of the earth with which the main and service pipes are covered than where the 130

service pipe leads from the top of the cock body.

With this connection of course, the frangible feature of the safety caps at the delivery end of the cock will be dispensed with, as the service pipe 31 and the coupling member 32 are attached directly to the delivery end of the cock, the coupling cap 32 serving as a sealing cap for the key and key seat, as clearly shown in Fig. 5.

It will be observed that in all forms of the development herein disclosed, the sealing cap at the socketed end of the key opposite the discharge end may be readily loosened or tightened so as to control, to a considerable extent, the seating of the key. For example, if the key should be difficult to turn, it may be eased off by turning back slightly the sealing cap at the socketed end of the key, and, conversely, if the key should be too loose, this sealing cap at the socketed end may be set up, or tightened, so as to bring the key snugly to its seat.

It will be noticed, further, that the body of the cock is of such shape and dimensions and so related to the projecting nipples and caps, that it is fitted to receive a wrench for inserting or removing the cock. In the form here disclosed, the body of the cock is made of substantially rectangular form although it will be obvious that other wrench or tool formations might be given to this body. The nipples and sealing caps, as shown, preferably lie within or at least do not project laterally beyond, the boundaries of the body portion, so that wrench or tool strain is not imposed upon any of these parts, but is applied directly to the body.

Such changes as are mechanical and obviously adoptions of equivalent expedients may be made from what is here shown without departing from my invention.

I claim:

1. In a device of the class described, the combination with a body having a key seat therethrough and an attaching nipple provided with a passage delivering to said key seat, a key fitted closely to the seat and having a passage adapted to register with the passage in said nipple and delivering at one end of said key, and sealing caps at each end of said body portion to seal the ends of the key, one of said caps sealing the key passage.

2. In a device of the class described, the combination with a body having a key seat therethrough and an attaching nipple provided with a passage delivering to said seat, a key seated closely to the seat and having a passage adapted to register with the passage in said nipple and delivering at one end of said key, and sealing caps at each end of said body to seal the ends of the key, one of said caps having means sealing the key passage and frangible under excessive pressure to release pressure therethrough.

3. In a device of the class described, the combination of a body portion having a tapering key seat therethrough and an attaching nipple provided with a passage leading to the tapering seat, a tapered key closely fitting said seat and having a passage adapted to register with the nipple passage and delivering at the small end of said key, a sealing cap secured to said body and sealing the large end of said key, a sealing cap secured to said body and sealing the small end of said key, said last mentioned cap having means frangible under excessive pressure to release pressure therethrough. 75

4. In a device of the class described, the combination of a body portion having a tapering key seat therethrough and an attaching nipple provided with a passage leading to the tapering seat, a tapered key closely fitting said seat and having a passage adapted to register with the nipple passage and delivering at the small end of said key, a sealing cap secured to said body and sealing the large end of said key, said cap having an aperture therein to give access to said key for turning, and a sealing cap secured to said body and sealing the small end of said key, said last mentioned cap having means frangible under excessive pressures to release pressure therethrough. 95

5. In a device of the class described, the combination of a body having a key seat therethrough and a lateral passage from said seat through the wall of said body, a key fitted closely to said seat and having a through passage from one end thereof to the side wall of said key and adapted to register with the lateral passage in said body, means for sealing and holding said key in its seat at one end, and means for sealing the key passage and key at the other end. 100

6. In a device of the class described, the combination of a body having a key seat therethrough and a lateral passage from said seat through the wall of said body, a tapered key fitted closely to said seat and having a through passage from one end thereof to the side wall of said key and adapted to register with the lateral passage in said body, means for sealing and holding said tapered key in its seat at one end, and means for sealing the key passage and key at the other end. 115

7. In a device of the class described, the combination with a body having a key seat, and a lateral passage from said seat through the wall of said body, said body also having a combined filling and emptying nipple, a key seated closely to said seat and having a passage extending longitudinally thereof and adapted to register with said lateral passage in said body, and to deliver to said combined filling and emptying nipple, and means associated with said nipple and frangible under excessive pressure to release pressure therethrough, said means being removable for 120 125 130

permitting the passage of a medium through said key passage in either direction.

8. In a device of the class described, the combination of a body having a key seat therethrough and a lateral passage from said seat through the wall of said body, a tapered key fitted closely to said seat and having a through passage from one end thereof to the side wall of said key and adapted to register with the lateral passage in said body, means for sealing and holding said tapered key in its seat at one end, and frangible means for sealing the key passage and key at the other end.
9. In a device of the class described, the combination with a body having a key seat therethrough and an attaching nipple provided with a passage delivering to said key seat, a key fitted closely to the seat and having a passage adapted to register with the passage in said nipple and delivering at one end of said key, a tool receiving projection on the said body opposite said attaching nipple, and sealing caps at each end of said body portion to seal the ends of the key, one of said caps sealing the key passage.

10. In a device of the class described, the combination with a body portion of exterior form to receive a wrench and having a key seat extending therethrough, an attaching nipple provided with a passage delivering to said key seat, a key fitted closely to the seat and having a passage adapted to register with the passage in the nipple and delivering at one end of the key, and sealing caps at each end of said body portion to seal the ends of the key, said caps being so disposed as not to project laterally beyond the boundaries of said body portion, one of said caps having means frangible under excessive pressure to release pressure therethrough.

11. In a device of the class described, the combination with a body having an attaching nipple and a combined filling and emptying nipple, said body being provided with a key seat communicating with said nipple, a key seated closely to said seat and having a passage extending longitudinally thereof and adapted to register with the passage and both of said nipples, and means associated with said combined filling and emptying nipple

and frangible under excessive pressure to release pressure therethrough, said means being removable for permitting the passage of a medium through said key passage in either direction. 55

12. In a device of the class described, the combination with a body having a tapered key seat, and a lateral passage from said seat through the wall of said body, said body also having a combined filling and emptying nipple, a tapered key seated closely to said seat and having a passage extending longitudinally thereof and adapted to register with said lateral passage in said body, and 60 to deliver to said combined filling and emptying nipple at the small end of said key, and means associated with said nipple and frangible under excessive pressure to release pressure therethrough, said means being removable for permitting the passage of a medium through said key passage in either direction. 65

13. In a device of the class described, the combination with a body having a key seat therethrough and a lateral passage from said seat through the wall of said body, said body also having a combined filling and emptying relief nipple, a key seated closely to said seat and having a passage extending longitudinally thereof for registry with said lateral passage and with said combined filling and emptying nipple, and a closure cap associated with said combined filling and emptying nipple for sealing the delivery end of said key and the passage therethrough. 70

14. In a device of the class described, the combination with a body having a tapering key seat therethrough and a lateral passage from said seat through the wall of said body, said body also having a combined filling and emptying relief nipple, a tapered key seated closely to said seat and having a passage extending longitudinally thereof for registry with said lateral passage and with said combined filling and emptying nipple at the small end of said key, and a closure cap associated with said combined filling and emptying nipple for sealing the small end of said key and the passage therethrough. 75

In testimony whereof I have hereunto set my hand. 80

CHARLES T. FORD. 85
